UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed May 1, 1923. Serial No. 635,872.

To all whom it may concern:

Be it known that I, HOMER P. CHANDLER, a citizen of the United States of America, residing at Mansfield, in the county of 5 Richland and State of Ohio, have invented certain new and useful Improvements in Conductor Supports, of which the following is a specification.

My invention relates to conductor supports and more particularly to that class of support for securing a trolley wire to an overhead hanger.

One of the objects of my invention is to produce a device which can be secured to a hanger, and then have the jaws which grip the trolley wire aline with the trolley wire without disturbing the relation between the clamp and the hanger, and then to move the jaws into gripping engagement with the trolley wire. Another object of my invention is to produce a device in which the jaws can be alined with respect to the hanger, and in which the jaws can be positively moved into or out of engagement with 25 the trolley wire. Other objects will be disclosed to those skilled in the art from the description herein of my preferred form of construction.

My invention resides in the new and novel construction, combination and relation of the various elements of which the invention is composed as herein described and shown in the accompanying drawing.

In the accompanying drawing:

Fig. 1 is a side view in elevation of my complete invention shown as engaging a trolley wire.

Fig. 2 is an end view of Fig. 1.

Fig. 3 is a sectional view of my invention taken on the line 3—3 of Fig. 1, showing a hanger in combination therewith and the jaws open to receive the trolley wire.

Fig. 4 is similar to Fig. 3 excepting the jaws are shown in gripping engagement with the trolley wire.

Fig. 5 is a sectional view on the line 5—5 of Fig. 4, and shows means whereby two of the elements have a limited relative rotation with respect to each other.

In the preferred embodiment of my invention I employ a supporting member 1 internally threaded to engage the threads on a stud 2 of the hanger H. The supporting member 1 is provided with a flange 3 to support an operating member 4. The

member 4 is provided with an internally projecting flange 5 which engages and rests upon the flange 3 and is supported thereby. The thickness of the flange 5 is preferably slightly less than the distance from the 60 upper face of the flange 3 to the upper face of the supporting member 1, so that when the device is installed upon the hanger H the operating member 4 will not bind, but will be free to rotate relative to the supporting member 1. The operating member 4 is provided with an internally threaded portion 6. Threadably engaging the internally threaded portion 6 of the operating member is an intermediate member 7 provided with threads 8 to engage with the threads on the operating member. The supporting member 1 is provided with a 65 projecting lug 9 which engages with a projecting lug 10 on the intermediate member 7. 70

It will be seen from Fig. 5 that the members 1 and 7 are free to rotate relative to each other, but have the said rotation limited by the engagement of the lugs 9 and 10. Projecting from the lower end of the member 7 is a lug 11 provided with an opening 75 to receive the pin 12. Secured to the lug 11 are two jaw members 13 provided with means 14 at their lower ends to engage a trolley wire 15. Adjacent the upper end of 80 the jaws 13 and projecting inwardly are lugs 16, and held in position with respect to the lug 11 by means of the pin 12 whereby the jaws are permitted to swing about the axis of the pin 12, but cannot rotate 85 otherwise with respect to the lug 11. 90

The jaws 13 are each provided near its upper end with an annular groove 17 formed by the adjacent flanges 18 and 19, and said groove may extend entirely around 95 the circumference of each jaw 13 or only part way around, depending upon the extent of the flanges 18 and 19. Positioned within the groove 17 of each jaw 13 is a flange 20 projecting from the lower portion of the operating member 4. The flange 20 engages the flange 19 to move the jaws 13 into engagement with the trolley wire and to hold them in said engagement. The flange 20 engages the flange 18 to move 100 the jaws out of engagement with the trolley wire or to open them to receive the trolley wire and to maintain the jaws in an open position. The jaws 13 and the operating member 4 are free to rotate relative to each 105 110

other. The member 4 is provided with a plurality of flat faces 21 to receive a wrench whereby it may be rotated.

It will be observed that the members 1 and 7 have a limited relative rotation with respect to each other, and that the member 4 is free to rotate with respect to the members 1, 7, and 13, and that the members 13 can not rotate relative to the member 7, but 10 are free to pivot with relation thereto about the axis of the pin 12. When the device is in position on a hanger the member 4 is held against a longitudinal movement with respect to the member 1, but the member 7 15 can move longitudinally with respect to the member 1 when the member 4 is rotated in either direction. It will also be observed that there is substantially no relative longitudinal movement of the member 4 with respect to the upper outer portions of the jaws 13 other than a pivotal action therebetween, and that the lugs 16 move with the member 7.

The operation of installing my invention 25 upon the hanger consists in first grasping the jaws 13 preferably with the hands and in placing the member 1 in engagement with the stud 2 of the hanger H. If the jaws are now rotated in the proper direction the lug 30 10 will be brought into engagement with the lug 9, and when this engagement takes place further rotation of the jaws will rotate the member 1 into full and secure engagement with the stud 2 until the upper face of the member 1 engages the lower face of the hanger H. After this operation the jaws 35 13 may not be in alinement with the trolley wire, but this alinement can be brought about by reversing the direction of rotation of the jaws and this reversal of rotation will not rotate the member 1, as the amount of back rotation would not exceed 180 degrees and there is a possible relative rotation of the members 1 and 7 of less than 360 degrees, depending upon the thickness of the lugs 9 and 10. Having alined the jaws with 40 respect to the trolley wire, if the jaws are in a closed position so as not to receive the trolley wire, the operating member 4 is rotated in a proper direction to cause the member 7 to move downwardly due to the threaded engagement, and this will cause the jaws to pivot about their point of engagement with the operating member and thereby force the jaws to open. Having opened the jaws, the trolley wire is placed in position between the jaws, and the operating member is then rotated in a direction to cause the member 7 to move upwardly until 45 the jaws engage the trolley wire. A wrench is now applied to the faces 21 of the operating member 4 and further rotation of the member 4 by means of the wrench will force the jaws into further and secure engagement with the trolley wire.

In Fig. 5 the lugs 9 and 10 are shown in two relative positions. In the position where the lugs engage (9—10'), this relation takes place when the jaws are rotated to rotate the member 1 into engagement with the hanger, and in the position where the lugs are shown separated, is illustrative of a position which the lugs may take after the jaws have been alined with respect to the trolley wire.

Modifications will occur to those skilled in the art from the disclosure which I have herein made, but I do not wish to be limited other than by my claims.

I claim:

1. A conductor clamp comprising a pair of jaws to grip the conductor, supporting means to secure the clamp to a hanger and means to permit the jaws to be rotated relative to the supporting means and to move the jaws either into or out of engagement with the conductor.

2. A conductor clamp comprising a pair of jaws to grip a conductor, supporting means to secure the clamp to a hanger, intermediate means to secure the jaws and supporting means together and to permit the jaws to rotate relative to the supporting means and to move the jaws either into or out of engagement with the conductor.

3. A conductor clamp comprising a pair of jaws to grip the conductor, supporting means to secure the clamp to a hanger and means to permit the jaws to be rotated relative to the supporting means to a limited extent and to move the jaws either into or out of engagement with the conductor.

4. A conductor clamp comprising a pair of jaws to engage a conductor, operating means engaging each jaw to move the jaws either into or out of engagement with the conductor and supporting means to secure the clamp to a hanger and having a relative rotation with respect to the jaws.

5. A conductor clamp comprising a gripping means to engage a conductor, supporting means to secure the clamp to a hanger, a member rotatable relative to the supporting means and supporting the gripping means, and operating means to engage the gripping means to move the gripping means either into or out of engagement with the conductor.

6. A conductor clamp comprising supporting means to secure the clamp to a hanger, gripping means to engage a conductor, operating means mounted on the supporting means and engaging the gripping means, intermediate means secured to the gripping means and movable longitudinally of the supporting means to force the gripping means into engagement with the conductor when moved in one direction and to release said engagement when moved in the other direction.

7. A conductor clamp comprising sup-

porting means to secure the clamp to a hanger, gripping means to engage a conductor, operating means mounted on the supporting means in rotative relation and 5 engaging the gripping means, intermediate means secured to the gripping means and movable longitudinally of the supporting means to force the gripping means into engagement with the conductor when moved 10 in one direction and to release said engagement when moved in the other direction.

8. A conductor clamp comprising supporting means to secure the clamp to a hanger, gripping means to engage a conductor, operating means mounted on the supporting means and engaging the gripping means, intermediate means secured to the gripping means and having limited rotation relative to the supporting means and 20 movable longitudinally of the supporting means to force the gripping means into engagement with the conductor when moved in one direction and to release said engagement when moved in the other direction.

25 9. A conductor clamp comprising a supporting means, and operating means supported thereon and rotatable relative thereto, a pair of jaws supported by the operating means and rotatable relative to the 30 operating means, intermediate means movable longitudinally of the supporting means and also supporting the jaws and coacting means on the operating means and the intermediate means to move the intermediate 35 means which in turn moves the jaws into engagement with the conductor when the operating means is rotated.

10. A conductor clamp comprising a supporting means, an operating means supported thereon and rotatable relative thereto, a pair of jaws secured to the operating means and rotatable relative thereto, intermediate means movable longitudinally of the supporting means and rotatable relative thereto and also secured to the jaws in pivotal relation thereto, and coacting means on the intermediate means and the operating means to move the intermediate means longitudinally of the supporting means and which in turn moves the jaws into engagement with the conductor.

11. A conductor clamp comprising a supporting means, an operating means supported thereon and rotatable relative thereto, a pair of jaws secured to the operating means and having a limited relative rotation, intermediate means movable longitudinally of the supporting means and rotatable relative thereto and also secured to the jaws in pivotal relation thereto, and coacting means on the intermediate means and the operating means to move the intermediate means longitudinally of the supporting means and which in turn moves the jaws into engagement with the conductor.

12. A conductor clamp comprising a supporting means, a pair of coacting members rotatably mounted on the supporting means, a pair of jaws secured to both members and movable into engagement with a conductor 70 when the members are rotated relative to each other.

13. A conductor clamp comprising a supporting means, a pair of coacting members rotatably mounted on the supporting means, 75 means on the supporting means to engage means on one of the members to limit its rotation and a pair of jaws secured to both members and movable into engagement with a conductor when the members are rotated relative to each other.

14. A conductor clamp comprising a supporting means, a pair of coacting members each rotatable relative to the supporting means and mounted thereon, the said members movable longitudinally to each other and a pair of jaws secured to each member and movable into engagement with a conductor when the members are moved in a relative longitudinal direction.

15. A conductor clamp comprising a pair of jaws, a pair of members secured to each jaw and movable longitudinally of each other to move the jaws into engagement with a conductor and supporting means to secure the parts to a hanger and having a limited rotation relative to the jaws.

16. A conductor clamp comprising a pair of jaws, a pair of members secured to each jaw and movable longitudinally of each other to move the jaws out of engagement with a conductor and supporting means to secure the parts to a hanger and having a limited rotation relative to the jaws.

17. A conductor clamp comprising a pair 135 of jaws, a pair of members secured to each jaw and movable longitudinally of each other to move the jaws, at will, into or out of engagement with a conductor and supporting means to secure the parts to a hanger 110 and to rotate relative to the jaws.

18. A conductor clamp comprising a pair of jaws, a member secured to the jaws in rotatable relation thereto, a second member secured to the jaws in hinged relation thereto, means to move the second member relative to the first member and thereby move the jaws into engagement with a conductor when the first member is rotated and means to secure the parts to a hanger.

19. A conductor clamp comprising a pair 125 of jaws, means to secure the clamp to a hanger, intermediate means to support the jaws in rotatable and longitudinally movable relation to the first means and rotatable means to move the intermediate means longitudinally to move the jaws into clamping relation with a conductor.

20. A conductor clamp comprising a support, a pair of jaws, a member to engage the 130

jaws and the support in rotatable relation, intermediate means supported by the member and engaging the jaws and longitudinally movable relative to the members and the support and means on the members engaging means on the intermediate means to move the jaws when the member is rotated.

21. A conductor clamp comprising means to grip a conductor, supporting means to secure the clamp to a hanger and having a limited relative rotation with respect to the gripping means, means to limit said relative rotation and means to move the jaws either into or out of engagement with the conductor at will.

22. A conductor clamp comprising supporting means, a member having a longitudinal and a limited rotatable movement relative to the supporting means, gripping means pivotally secured to said member, and means to move the member longitudinally and the gripping means into or out of engagement with a conductor.

23. A conductor clamp comprising a supporting means, gripping means to engage a conductor, means to hinge the gripping means together said hinging means movable towards and away from the supporting means and means to move the said hinging means towards or away from the supporting means at will.

24. A conductor clamp comprising a supporting means, gripping means to engage a conductor, rotatable means engaging the

35 gripping means and forming a fixed fulcrum with the gripping means, an intermediate member engaging the rotatable means and forming a movable fulcrum with the gripping means and to move the said fulcrum when the rotatable means is rotated to move 40 the gripping means into engagement with the conductor.

25. A conductor clamp comprising a supporting means to attach the clamp to a hanger, a pair of members movable longitudinally to each other and each having 45 pivotal means, gripping means secured to each of the pivotal means, and means to move the pivotal means relative to each other to move the gripping means into engagement with a conductor.

26. A conductor clamp comprising a supporting means, a member in telescopic relation to the supporting means and a limited rotation with respect to the supporting means, gripping means secured to the members and means to move the members in telescopic relation to the supporting means to move the gripping means into engagement with a conductor.

27. A conductor clamp comprising a supporting means, a conductor gripping means mounted to rotate relative to the supporting means and means to move the gripping means either into or out of engagement with the conductor.

In testimony whereof I affix my signature.
HOMER P. CHANDLER.
